SHIELD

Gertrude Stovall, Los Angeles, Calif.

Application September 16, 1941, Serial No. 411,040

1 Claim. (Cl. 2—174)

This invention relates to a shield and more particularly pertains to a shield which is especially applicable for use in protecting the face of a person while subjecting the head and hair to the action of heated air delivered from a drier as in beauty parlor operations.

An object of the invention is to provide a shield which is shaped and adapted to be applied to the head of a person in a fashion to substantially encircle the scalp and project outwardly therefrom so as to deflect the portions of the stream of heated air directed toward the scalp from a drier which ordinarily flow over the face and neck of the person being treated, and yet expose the main portion of the hair to the action of the drier.

Another object is to provide a shield of the above character which is so constructed that a shield of predetermined size may be readily fitted to heads of various sizes whereby a single sized shield may be generally used.

A further object is to provide a shield of annular formation which is adapted to be contracted to effect reduction of its inner periphery.

With the foregoing objects in view, together with such other objects and advantages as may subsequently appear, the invention is carried into effect as illustrated by way of example in the accompanying drawing, in which:

Fig. 1 is a plan view of the shield showing it in its normal form and depicting one embodiment of the invention;

Fig. 2 is a perspective view of the shield shown in Fig. 1 showing it in its assembled position;

Fig. 3 is a perspective view depicting the mode of applying the shield;

Fig. 4 is a plan view of a modified form of the shield;

Fig. 5 is a perspective view of the shield shown in Fig. 4 showing it as assembled.

Referring to the drawing more specifically, A indicates generally the blank of the shield which is formed of thin sheet flexible materials such as paper and is annular in form, but which is provided with a radially extending gap 6 affording normally spaced opposed end marginal portions 7 and 8 adapted to be brought into overlying relation to each other. The blank A is normally flat but on the end portions 7 and 8 thereof being brought into an overlapped position will assume a frusto-conical shape. A narrow upstanding flange 9 is formed on the inner perimeter of the blank to reinforce and stiffen its inner margin. The split annulus thus formed is contractible circumferentially and diametrically by drawing

the end portions thereof into overlying relation to each other which action as above stated converts the normally flat blank into an annulus of frusto-conical formation, as shown in Figs. 2 and 5, the inner and outer circumferences and diameters of which annulus will vary according to the extent of overlap of the end margins 7 and 8.

Means are provided for fastening the overlapped end portions of the blank together which in the embodiment of the invention shown in Figs. 1, 2 and 3, embodies a tongue 10 formed on the end edge of the marginal portion 7 and a series of narrow slits or slots 11 formed in the marginal portion 8 with any one of which slots the tongue 10 is adapted to be engaged. The outer end of the tongue 10 is rounded to facilitate its insertion in a slot 11 and the upper or inner edge of the tongue is formed with a V-notch 12 one side of which extends in continuation of the end edge of the marginal portion 8 and which notch is adapted to be disposed astride the portion of the blank forming the inner end of a slot 11 in a fashion to effect locking engagement therewith. The inner ends of the slots 11 are correspondingly spaced inwardly from the inner margin of the blank a distance equal to the distance between the inner margin of the blank and inner end of the V-notch 12 so that when the overlapped ends of the blank are interconnected the overlying peripheral portions thereof will be in register or substantially so.

The outer end portions of the slots 11 are curved away from the end margin 8 as indicated at 13 to provide along the inner margin of the slot a lip 14 which is adapted to be elevated slightly and thereby facilitate insertion of the tongue 10 into the slot.

A modified form of the fastening means for the overlapped end portion of the blank is shown in Fig. 5 which comprises a spring wire clip 15 adapted to be positioned astride the overlapped end portions as illustrated so as to grip the end portions in the fashion common to such clips.

The annulus thus formed is adapted to be applied to the head of a person to encircle the scalp as shown in Fig. 3; it being adjusted in its circumferential length and diameter to loosely fit the head by varying the extent of overlap of its end portions.

While the annulus as above described may be self supporting on the head there may be occasions where it is desirable to employ a fastener to insure maintaining the shield in place and accordingly I have equipped the shield with such

fastener which is here shown as comprising a narrow line such as ribbon or thread 16 one end of which is engaged with the inner marginal portion of the blank as at the base of the flange 9, and the intermediate portion of which line is rove through a pair of spaced holes or eyelets 17 and 18 in portions of the inner margin of the shield opposing the engaged end of the line. As here shown the engagement of one end of the line with the shield is effected by forming the line with a knot 19 and roving the line through an opening or eyelet 20 in the inner marginal portion of the shield from the outside so that the knot 19 will seat on the outer margin of the opening 20; the knot being larger than such opening. The line is then passed through the opening 17 from the inside of the shield or flange and is then extended along the outer face of the flange to the opening 18 and brought through the latter from the outside so that the free end of the line may be brought forwardly and upwardly from the inner margin of the shield and engaged with the end portion of the line extending between the openings 17 and 20.

In applying the shield the line is adjusted so as to overlie the head as shown in Fig. 3, with

the free end of the line fastened in place either by tying or by means of a hair pin.

When the shield is applied it will serve to protect the eyes and face of the wearer from streams of heated air delivered from a hair drier and permits the subject to utilize the eyes in reading or otherwise during the hair drying operation.

While I have shown and described a specific embodiment of my invention I do not limit myself to the exact details of construction set forth, and the invention embraces such changes, modifications and equivalents of the parts and their formation and arrangement as come within the purview of the appended claim.

I claim:

A shield for application to the head of a person comprising a divided frustro-conical annulus of flexible sheet material, means for holding said annulus in various contracted positions with the divided portions overlapped to vary the diameter and circumferential dimensions thereof, said annulus being formed with a series of holes along its inner marginal portion, and a line rove through said series of holes having one end engaged with said annulus.

GERTRUDE STOVALL.
